Assistant Examiner — Cleso Moore, Jr.

(57) **CLAIM**

The ornamental design for a storage box for helmet as shown and described.

DESCRIPTION

1. Storage box for helmet

1.1 : Perspective

1.2 : Front

1.3 : Back

1.4 : Left

1.5 : Right

1.6 : Top

1.7 : Bottom

Reproduction 1.1 is a perspective view of a storage box for helmet showing our new design; reproduction 1.2 is a front elevation view thereof; reproduction 1.3 is a rear elevation

(Continued)

view thereof; reproduction **1.4** is a left side elevation view thereof; reproduction **1.5** is a right side elevation view thereof; reproduction **1.6** is a top plan view thereof; reproduction **1.7** is a bottom plan view thereof.

1 Claim, 7 Drawing Sheets
